ATTORNEY.

UNITED STATES PATENT OFFICE.

GEORGE H. AMEY, OF FRESNO, CALIFORNIA.

HOSPITAL BED-MATTRESS.

1,347,666.

Specification of Letters Patent. Patented July 27, 1920.

Application filed October 23, 1919. Serial No. 332,727.

To all whom it may concern:

Be it known that I, GEORGE H. AMEY, a citizen of the United States, and resident of Fresno, in the county of Fresno and the 5 State of California, have invented a new and useful Improvement in Hospital Bed-Mattresses, of which the following is a specification.

My invention relates to a bed mattress 10 and more especially to a mattress used in hospitals for patients who can not readily be moved.

The object of my invention is to provide a mattress which has a center of semi- 15 flexible material stretched in a rigid frame, said mattress having a removable section from the side so that a frame containing either a section of mattress or a bed pan can be readily inserted therein, or the section 20 of the mattress can be left out so that a patient lying thereon can be washed without soiling the mattress.

I accomplish these and other objects hereinafter referred to by means of the device 25 hereinafter described and illustrated on the accompanying drawing in which Figure 1 is a perspective view of the mattress with a section removed from the side, showing the slideway. Fig. 2 is a section of the 30 mattress complete with removable frame. Fig. 3 is the removable section of the mattress without the base or frame. Fig. 4 shows an ordinary bed pan arranged on a slide adapted to fit in the recess and on the 35 slideway. Fig. 5 is a cross-sectional view of the mattress along the line $\alpha-\alpha$ in Fig. 1. Fig. 6 is a cross-sectional view of the mattress along line $y-y$ on Fig. 1. Fig. 7 is an enlarged view of the mattress bracing element. 40

In said drawing B represents the mattress having a portion cut away from the side forming a recess designated on the drawing as B^1 . As a part of the mattress I have 45 formed a rigid frame around it, C and C^1 representing the ends, C^3 and C^2 the sides, and C^4 , C^5 and C^6 the three sides of the recess B^1 . D are a plurality of flexible strips extending through the center of the 50 mattress and are attached to the ends of the frame C and C^1 by rivets or bolts N. 4 represents sectional views of bed posts, and 3 are brackets attached to the corners of the mattress which encircle the posts 4. 3^a 55 are set screws to fasten the brackets 3 to posts 4. The strips D should be rigid

enough so that when the mattress is suspended from its corners it will not double, or unduly sag when the weight of a person is thereon. M represents the hair or felt 60 with which the mattress is stuffed. The opening B^1 is encircled by a slideway designated on the several sides of the opening as E, E^1 and E^2 . The slideway is constructed at the approximate vertical center 65 of the mattress so that either side of the mattress can be used. G represents the removable section of the mattress complete as shown in Fig. 2. F, F^1 and F^2 are grooves running around the two sides and the back, 70 the grooves being constructed so that the slideways E, E^1 and E^2 will readily enter therein. The front of the grooves F^1 and F^2 are formed so they will bind the slide-ways E^1 and E^2 when the section is in place 75 on the mattress. In order to make the mat- 80 tress more rigid I have formed two dowel holes P and P^1 one on each side of the opening B^1 and into the portion of the frame C^2 , and have attached dowel pins J^1 and J^2 to the front end of base L, the arrangement 85 being such that when the frame L is in place on the mattress the dowel pins J^1 and J^2 , (which are connected by a rod J), enter the dowel holes P and P^1 , thus keeping it from spreading. Fig. 7 shows the dowel pins J^1 and J^2 and connecting rod J separately. This is used when the opening B^1 is not 90 closed, for the purpose of holding the mat- 95 tress rigid. This may be necessary when giving the patient a dousch or in bathing him. The top of the base L slopes from the front toward the rear. H is a section of the mattress formed thicker at the back than at the front so that it will readily fit on the top of the base L and when assembled the top of the section H should be on a common plane with the top of the mattress B. In Fig. 3 the thicker end of the mattress has been indicated as H^1 and the thinner end 100 as H^2 . 6 are mattress ties.

In Fig. 4 I have shown a modified form of base L^1 on which is attached a bed pan K. The grooves F^1 and F^2 correspond with the grooves of the same letters in base L. 105 t are holes through the mattress frame. R is a U brace, the ends of which pass into holes t and t , the purpose being to make the frame more rigid.

I claim as new and ask for Letters Patent: 110

1. In a device of the character described the combination of a mattress having a rigid

- 2 rectangular frame within the mattress near the outside edge thereof, flexible metal straps, extending through the mattress and attached to opposite sides of the frame, a 5 section of said mattress having been removed from one side thereof, slideways on opposite sides of the opening formed where said section is removed and a frame adapted to slide on said slideways having the upper 10 surface sloping downward from the outside edge toward the center thereof, and a section of mattress thicker on one edge than on the opposite edge adapted to fit within the opening on the top of frame, to form an 15 approximately level surface with the top of the mattress, substantially as described.
2. In a device of the character described the combination of a mattress attached to a rigid rectangular frame, metal flexible 20 straps extending through the mattress attached to opposite sides of the frame, said mattress having a section removed from one side thereof, a slideway around the sides of the opening where said section was re- 25 moved, a slide adapted to carry a bed pan slidably fitted on the slideway, and a sepa-

rate section of mattress adapted to cover said opening slidingly fitted on the slideway, substantially as described.

3. In a device of the character described 30 the combination of a mattress having a section on one side thereof removed, the opening formed by the removal of said section having a rigid slideway on two opposite sides thereof, frames constructed to slide 35 within said slideway, one of said frames having a rigid base which slopes downward from the outside edge toward the center of the mattress, and a separate section of mattress constructed to fit on said base so that 40 the top is on approximately the same plane as the top of the mattress, and one of said frames having a bed pan attached on the top thereof constructed so that when assembled with the mattress the top of the bed pan is 45 approximately on the same plane as the top of the mattress, substantially as described.

GEORGE H. AMEY.
